(57) CLAIM

The ornamental design for a helmet rack wall mount, as shown and described.

DESCRIPTION

FIG. 1. is a first perspective view of a helmet rack wall mount showing my design;

FIG. 2. is another perspective view thereof;

FIG. 3. is a back perspective view thereof;

FIG. 4. is a front perspective view thereof;

FIG. 5. is a left perspective view thereof;

FIG. 6. is a right perspective view thereof;

FIG. 7. is a top perspective view thereof; and,

FIG. 8. is a bottom perspective view.

The broken lines in the drawings depict portions of the helmet rack wall mount that form no part of the claim.
